CLAIM

The ornamental design for a card display stand, as shown and described.

DESCRIPTION

FIG. 1 is a front elevational view of a card display stand, showing my new design, the rear and side views being identical thereto;

FIG. 2 is a top plan view thereof;

FIG. 3 is a bottom plan view thereof;

FIG. 4 is an edge elevational view, the other edge views being identical thereto.

All of the receptacles are for retaining business cards or the like.

FIG. 4

FIG. 2

FIG. 3

FIG. 1
